UNITED STATES PATENT OFFICE.

ALBERT HENRY MIDGLEY, OF ACTON VALE, ENGLAND, ASSIGNOR OF ONE-HALF TO
CHARLES ANTHONY VANDERVELL, OF ACTON VALE, ENGLAND.

LAMP-SIGNALING ARRANGEMENT.

1,191,528.

Specification of Letters Patent. Patented July 18, 1916.

Application filed February 24, 1916. Serial No. 80,199.

To all whom it may concern:

Be it known that I, ALBERT HENRY MIDGLEY, a subject of the King of Great Britain and Ireland, and residing at War-
5 ple Way, Acton Vale, in the county of Mid-
dlesex, England, have invented certain new
and useful Improvements in and Relating
to Lamp-Signaling Arrangements, of which
the following is a specification:

10 This invention relates to lamp-signaling
arrangements, more especially for use on
aircraft or for other purposes, the main ob-
ject of the invention being to provide a very
light arrangement of this kind.

15 The invention mainly consists in a lamp-
signaling arrangement comprising in com-
bination with a revolver-shaped lamp-holder
having a handle provided with a trigger, a
reflector mounted thereon preferably in an

20 adjustable manner, an opaque member pro-
vided in front of the lamp and a shutter op-
erated around the lamp by means of said
trigger in such a manner that while the
shutter is normally kept in such a position
25 as to prevent the light reaching the reflector,
when operated by the trigger it is removed
from said position in order to allow the light
to reach the reflector.

The invention also consists in the details
30 of construction hereinafter more particu-
larly referred to and specifically claimed.

The invention is illustrated by way of ex-
ample in the accompanying drawings in
which:—

35 Figure 1 is a sectional elevation; Fig. 2
a front view partly cut away; Fig. 3 a sec-
tional plan; and Fig. 4 a back view partly
cut away of the improved apparatus.

Referring to the drawings: *a* is a lamp-
40 holder for the lamp *b* which is provided
with a revolver-shaped hollow handle *c*, in
which is mounted a trigger *d*, and an elec-
tric switch *e*, the spring contact *e*₁ of which
is adapted to be brought into contact with a
45 fixed contact *e*₂ by means of a switch handle
*e*₃, when the handle *c* is grasped for signal-
ing purposes.

f, *f*₁ are the leads to the lamp, *g*, *g*₁ are
adjustable stops for the trigger *d*, and *h*
50 a cover for closing the top of the revolver-
shaped hollow handle *c*.

i is a parabolic reflector provided with a
base *i*₁ by means of which it is slidably
mounted on the holder *a*.

j, *j*₁ are adjusting screws provided with 55
milled heads and mounted in lugs *k*, *k*₁
formed on the lamp-holder *a*, by means of
which the reflector can be shifted relatively
to the lamp in order to focus the latter.

The shutter consists of two parts *l*₁, *l*₂, of 60
a divided hemisphere interposed between
the back of the lamp *b* and the reflector *i*
and normally kept in that position by means
of a spring *v* hereinafter referred to. The
two parts *l*₁, *l*₂ of the shutter are arranged 65
to pivot from the front to the back of the
lamp around an upper and lower pivot *m*₁,
*m*₂, which are secured to a bridge member *n*
70 attached in its turn to the lamp-holder *a*
by means of lugs *n*₁, *n*₂. The bridge mem-
ber *n* also carries a sleeve *o* adapted to re-
ceive an opaque removable cap *p* which cov-
ers the front of the lamp.

q is a plate of transparent material, such
as glass or celluloid, which is arranged in 75
front of the reflector *i* and is clamped in
position thereto by means of a clamping
ring *r*, preferably through the interposition
of an india-rubber ring *s*.

The operation of the shutters by means 80
of the trigger *d* is effected through the in-
termediary of links *t*₁, *t*₂ attached to the
parts *l*₁, *l*₂ of the shutter respectively, and
to a lever *u* which is under the control of
the spring *v* hereinbefore referred to, and 85
of a rod *d*₁ attached to a fork-shaped mem-
ber *d*₂, which also carries a roller *d*₃ acted
upon by the trigger *d* in such a manner as
to cause the rod *d*₁ to slide through the lamp-
holder.

*u*₁ is an adjustable stop secured to the
bridge member *n* and adapted to come into
contact with the lug *u*₂, provided on the lever
u in order to suddenly stop the movement
of the latter and thereby damp the move- 95
ment of the shutters when they reach their
end position.

w is a sight which is arranged to pass
through the reflector *i* to which it is at-
tached, and through the transparent plate *q*, 100
the object of this arrangement being to bring
the sight as near as possible the focus of the
parabolic reflector, thereby increasing the
accuracy of sighting.

x is a handle which is attached to the base 105
*i*₁ of the reflector by means of a clamping
ring *x*₁, the object of this handle being to
steady the lamp.

Having now described my invention, what I claim as new and desire to secure by Letters Patent is:—

1. A lamp signaling device comprising in combination a revolver-shaped lamp holder, a trigger, a reflector and a lamp all mounted on said lamp holder, a pivoted hemispherical shutter, means for operating said shutter from said trigger, and an opaque member arranged in front of the lamp, as and for the purpose set forth.
2. A lamp signaling device comprising in combination a revolver-shaped lamp holder, a trigger, a reflector and a lamp all mounted on said lamp holder, a shutter consisting of two parts of a divided hemisphere, pivots for the two parts of said divided hemisphere, means for operating said shutter from said trigger, and an opaque member arranged in front of the lamp, as and for the purpose set forth.
3. A lamp signaling device comprising in combination a revolver-shaped lamp holder, a trigger, a reflector and a lamp all mounted on said lamp holder, means for sliding the reflector on the lamp holder, a pivoted hemispherical shutter, means for operating said shutter from said trigger, and an opaque member arranged in front of the lamp, as and for the purpose set forth.
4. A lamp signaling device comprising in combination a revolver-shaped lamp holder, a trigger, a reflector and a lamp all mounted on said lamp holder, adjustable stops for the trigger, a pivoted hemispherical shutter, means for operating said shutter from said trigger, and an opaque member arranged in front of the lamp, as and for the purpose set forth.
5. A lamp signaling device comprising in combination a revolver-shaped lamp holder, a trigger, a reflector, a lamp and a switch all mounted on said lamp holder, a pivoted hemispherical shutter, means for operating said shutter from said trigger, and an opaque member arranged in front of the lamp, as and for the purpose set forth.
6. A lamp signaling device comprising in combination a revolver-shaped lamp holder, a trigger, a reflector and a lamp all mounted on said lamp holder, a shutter consisting of two parts of a divided hemisphere, pivots for the two parts of said divided hemisphere, a bridge member attached to the lamp holder and carrying said pivots, means for operating said shutter from said trigger, and an opaque member arranged in front

of the lamp, as and for the purpose set forth.

7. A lamp signaling device comprising in combination a revolver-shaped lamp holder, a trigger, a reflector and a lamp all mounted on said lamp holder, a shutter consisting of two parts of a divided hemisphere, pivots for the two parts of said divided hemisphere, a bridge member attached to the lamp holder and carrying said pivots, means for operating said shutter from said trigger, a sleeve on the bridge member arranged to surround the lamp, and an opaque member mounted on said sleeve and covering the front of the lamp, as and for the purpose set forth.

8. A lamp signaling device comprising in combination a revolver-shaped lamp holder, a trigger, a reflector and a lamp all mounted on said lamp holder, a shutter consisting of two parts of a divided hemisphere, pivots for the two parts of said divided hemisphere, means for operating said shutter from said trigger comprising a sliding rod, a lever, a spring acting on said lever and connecting links between the lever and the two parts of the shutter, and an opaque member arranged in front of the lamp, as and for the purpose set forth.

9. A lamp signaling device comprising in combination a revolver-shaped lamp holder, a trigger, a reflector and a lamp all mounted on said lamp holder, a shutter consisting of two parts of a divided hemisphere, pivots for the two parts of said divided hemisphere, means for operating said shutter from said trigger comprising a sliding rod, a lever, a spring acting on said lever and connecting links between the lever and the two parts of the shutter, an adjustable stop for said lever, and an opaque member arranged in front of the lamp, as and for the purpose set forth.

10. A lamp signaling device comprising in combination a revolver-shaped lamp holder, a trigger, a reflector and a lamp all mounted on said lamp holder, a pivoted hemispherical shutter, means for operating said shutter from said trigger, an opaque member arranged in front of the lamp, and a sight passing through the reflector in the proximity of the lamp, as and for the purpose set forth.

In testimony whereof I have signed my name to this specification.

ALBERT HENRY MIDGLEY.
